UNITED STATES PATENT OFFICE.

ERNST GLASS, OF TROSSINGEN, GERMANY, ASSIGNOR TO MATTH. HOHNER AKT. GES.,
OF TROSSINGEN, WURTEMBERG, GERMANY.

DEVICE FOR GIVING CORRECT NOTES AND HARMONIES IN MOUTH ORGANS

Application filed August 23, 1926, Serial No. 130,852, and in Germany May 12, 1926.

The present invention relates to an improvement on the existing devices for giving correct notes and chords in mouth organs, in which a mouthpiece is provided on 5 the one hand and a slide provided with holes on the other in order to enable the desired combination of notes to be produced. According to the present invention this device is considerably simplified in that the mouth- 10 piece and slide are in one piece so that the desired note can be readily and accurately adjusted and produced with certainty. Given a suitable arrangement of the notes, that is, a suitable arrangement or formation 15 of the blowing orifices, the device can also serve as a harmonizer.

The new device is characterized not only by its simplicity of construction and superior 20 adjustability, but also by economy of material and increased possibilities of application. Its construction also adapts it for mass production by machinery. Finally the instruments are stronger than those hitherto known.

25 A typical embodiment of the subject of the present invention is more fully illustrated in the drawing.

Figures 1 and 2 are respectively a front elevation and plan of the instrument.

30 Figures 3 and 4 are an end elevation and cross section of the same.

Figure 5 is a bottom view, and Figure 6 shows on a much larger scale a bottom view of the braking spring arrangement of the 35 mouthpiece.

The instrument is a kind of mouth organ 40 the reeds *a* of which are situated as usual in or above the holes of the mouth board *b* and are caused to sound by blowing or suction. They are enclosed in a sounding or protective casing *c* made in the usual manner 45 which is legibly impressed with a scale of notes *d* corresponding to the range of the instrument and also with the lettering *e* of the notes.

The blowing side of the instrument is provided with a strip *f* provided with blowing apertures *g* corresponding to the chambers in which the reeds are located. This strip *f* also serves as a guide for the sliding mouthpiece *h* which also serves as an adjusting slide, and is provided with blowing apertures *i*. The mouthpiece *h* embraces the guide strip *f* by means of its edges *k*, which 55 are suitably bent round over strip *f* so that

it can slide thereon and also fit closely against it. In addition to providing a bearing and guiding surface, the strip *f* provides an effective stiffening which makes the construction very strong. The strip *f* comprises 60 a central body portion having angular extensions.

In order to hold the mouthpiece automatically in the adjusted position, a braking spring, namely a flat spring *l* is provided on 65 its under side. This is carried on the overlapping portion *k* of the mouthpiece *h* and its ends bear elastically against the adjacent wall of the guide strip *f*.

The spring *l* is held by claws *m* provided 70 on the bent over portion *k* of the mouthpiece *h*, which grip it in such a manner that it is curved and pressed against the corresponding guide wall of the guide bar *f*.

This provides a simple method of mounting the spring *l* and all springs used in such 75 devices are mechanically placed under identical and correct tension.

To facilitate sliding the mouthpiece *h* small upward bends *n* are provided at both 80 ends of same.

In addition means are provided to stop the mouthpiece in its two lateral terminal positions and prevent it from being pushed too far or from being accidentally slid off 85 the instrument altogether. With this object the blowing side of the cell panel *b* is provided with stops for example, in the form of small screws *o* and the mouthpiece *h* is provided with slots *p* extending so far into the 90 bends *n* that the head of the stop screw *o* can engage in the slot *p* the end of which limits the movement of its mouthpiece *h* by coming in contact with the screw *o*.

On the upper side a pointer *q* projecting 95 from the mouthpiece *h* moves over the characters *e* relating to the notes, and thus facilitates correct adjustment for the notes.

The number, position, dimensions and shape of the blowing apertures *i* in the 100 mouthpiece may be varied to any extent. Hence, the combination of the apertures *i*, the notations *e*, and the pointer *q*, enable a person without musical training to readily sound suitable chords and harmonies. I am 105 aware of the fact that slideable mouthpieces for harmonicas have been previously proposed, but such mouthpieces did not operate to enable chords and harmonies to be sounded.

What I claim is:—

1. A mouth organ comprising a body portion having a front edge provided with openings corresponding to the chambers in which the reeds of said mouth organ are located, 5 which the reeds of said mouth organ are located, a guide strip connected to said front face and having apertures corresponding to said chambers, said guide strip having angular projecting portions above and below said front face, a mouthpiece having inturned angular portions engaging the said angular projecting portions of the guide strip, and a curved blade spring connected to the said mouthpiece, the ends of the said blade spring therewith a spring adapted to slidably and 10 frictionally bear against the said mouth organ.
- 15 2. A mouth organ comprising a body por-

tion having a front face provided with openings corresponding to the chambers in which the reeds of said mouth organ are located, 20 a guide strip connected to said front edge and having openings aligned with said chambers, said guide strip having angular projecting portions above and below said front face, a mouthpiece having inturned angular portions engaging the said angular projecting portions of the guide strip, and a curved blade spring connected to the said mouthpiece, the ends of the said blade spring being adapted to frictionally bear against 25 one of said angular projecting portions.

In testimony whereof I affix my signature.

ERNST GLASS.
